CONTROL APPARATUS

Franklyn Y. Carter, William E. Cowley, and Ernest J. Dillman, Detroit, Mich., assignors to Detroit Lubricator Company, Detroit, Mich., a corporation of Michigan

Application April 9, 1940, Serial No. 328,736

6 Claims. (Cl. 137—153)

Our invention relates generally to control apparatus and more particularly to valve means for controlling the flow of a refrigerant medium.

One object of the invention is to provide means for automatically regulating the flow of refrigerant in a refrigerating apparatus.

A further object is to provide means for preventing flow of refrigerant by the automatic means.

A further object is to provide automatic means to operate the flow preventing means.

The invention consists in the improved construction and combination of parts, to be more fully described hereinafter and the novelty of which will be particularly pointed out and distinctly claimed.

In the accompanying drawing, to be taken as a part of this specification, there is fully and clearly illustrated a preferred embodiment of our invention, in which drawing—

Figure 1 is a diagrammatic view of a control system showing the control apparatus in central vertical cross-section;

Fig. 2 is a view substantially along the line 2—2 of Fig. 1 looking in the direction of the arrows, and

Fig. 3 is a partial diagrammatic view showing the modified form of the control apparatus in central vertical cross-section.

Referring to the drawing by characters of reference, the numeral 1 designates generally a casing member having an inlet 2, an outlet 3 and a vertically extending, longitudinal passageway 4. The inlet 2 opens into an annular chamber 5 in which is placed a strainer 6 through which the fluid passes as it flows from the chamber 5 into a passageway 7 and then into the passageway 4. The passageway 4 opens downwardly into a valve chamber 8 and has screwthreaded thereinto a seat member 9 having a valve port 10. From the chamber 8 the fluid flows through the outlet 3. The chamber 8 has an open lower end which opens through a lower end 11 of the casing member 1. A hollow, cylindrical valve carrier member 12 fits within and is guided within the chamber 8 and has a pair of shoulders 12^a, 12^b spaced one above the other and adjacent the upper end of the carrier member 12. A valve member 13 having an annular flange portion 13^a positioned between the shoulders 12^a, 12^b is co-operable with the port 10 to control flow of fluid therethrough. The flange portion 13^a is held against the lower shoulder 12^a by means of a helical coil spring 13^b which is concentric with the valve member 13 and is held under compression

between the flange portion 13^a and the upper shoulder 12^b. The flange portion 13^a has a diameter somewhat smaller than the inside diameter of the carrier member 12 into which it fits so that the valve member 13 may have lateral movement for adjusting itself to its port 10. The shoulders 12^a, 12^b should be spaced apart sufficiently, and the spring 13^b should be sufficiently collapsible, so that when the carrier member 12 is in its position furthest away from port 10, the valve member 13 may be moved to its position in engagement with the port 10.

The valve member 13 is moved in an opening direction by means of a temperature-sensitive power element 14 having a bulb element 15 and a movable diaphragm wall member 16. A plurality of thrust pins 17 transfer movement from the diaphragm member 16 to the valve carrier member 12 and act to oppose closing movement of the valve carrier member 12 due to the expanding force of a helical coil compression spring 18 which is under compression between a shoulder 19 of the member 12 and a flange 20 extending outwardly from the lip portion of an inverted cup-like adjustable abutment member 21. A tubular member 22 has one open end thereof secured to the end 11 as by means of bolts 23 (only one of which is shown) and is positioned with its hollow interior aligned with the chamber 8. A movable cylindrical abutment member 24 extending longitudinally of the member 22 has at its lower end portion a peripheral outwardly extending flange 25 which abuts against an internal transverse wall 26 of the member 22. The member 24 is screw-threaded to receive the internal threaded portion of the cup-shaped member 21. The member 22 has a hollow, radially, outwardly extending boss 27 in which is journaled an adjustment means 28 having a spur gear portion 29, which portion cooperates with a toothed or gear portion of the flange 25 for rotation of the member 24 so that the member 21, which is held against rotation as will be hereinafter described, is vertically reciprocated to adjust the force exerted by the spring 18, and which adjustment acts in like manner to the prior art superheat adjustment for thermostatic expansion valves. Suitable packing material is held within the boss 27 and tightly against the means 28 by a packing gland nut 30 to prevent leakage of fluid from the interior of the member 22. The boss 27 is externally threaded for reception of a cap member 31 which is screw-threaded thereto, after adjustment, to form a second fluid-tight seal to prevent loss of fluid should the packing leak. A gasket 31^b may be

inserted intermediate the end wall of the boss 27 and the cap member 31 if desired.

The transverse wall 26 has a central aperture therethrough in which is secured in a suitable manner, as by solder, the lower end portion of a hollow tubular member 32 which extends upward from the wall 26 and into the chamber 8. The outside periphery of the member 32 is preferably hexagonal in cross-section and fits within the inside diameter of the member 24 similarly to a hexagon within a circumscribed circle. The tubular member 32 serves as an axle about which the member 24 rotates. The tubular member 32 also extends through a central hexagonal aperture in the transverse wall portion of the inverted cup-like member 21 and acts to guide and prevent rotation of the member 21.

Substantially fitting and reciprocal within the member 32 is a rod or thrust member 33 which has its upper end portion within the chamber 8 and its lower end portion within a chamber 34 formed in the lower end portion of the hollow member 22 by the transverse wall 26. The upper end portion of the rod 33 has a head portion 33a which is operable to engage the lower end of, and to force the valve member 13 against the force of the spring 13b so that member 13 engages the seat member 9 to stop flow of fluid through the valve port 10 even though the carrier member 12 may be moved downward to valve open position.

An annular member 58 is secured in fluid-tight relationship to the lower surface of wall 26 and has a pair of downwardly extending concentric flange portions 51, 52. The upper ends of a pair of concentric bellows members 53, 54 are secured respectively to the portions 51, 52, and the other or downward end of the bellows members 53, 54 are secured to the inner and outer peripheral portions respectively of a lower movable annular plate member 55. The plate member 55 is sealed in fluid-tight relationship to a disk-like abutment member 56 which is carried by, and sealed in fluid-tight relationship to, the lower end portion of the thrust rod 33. The lower external end portion of housing member 22 is threaded so that a cap member 57 may be securely affixed thereto to close the lower open end of chamber 34. The cap member 57 has an internal shoulder against which a gasket 58 is positioned, and which gasket is held intermediate the lower end wall of the member 22 and the shoulder of the cap member 57 to prevent flow of fluid from the chamber 34. The bellows 53 and abutment member 56 together with the annular members 50, 55 act as a seal to prevent the fluid which flows between the rod 33 and member 32 from escaping to atmosphere.

The bellows members 53, 54 and annular members 50, 55 cooperate to form an expansible-contractible chamber 59 which acts, upon expansion, to move the abutment member 56 and attached rod 33 downward against the force of a helical coil spring 60 which is positioned and held under compression between the abutment member 56 and cap member 57. The spring 60 is held in position by a pair of circular raised portions of the members 56, 57 which substantially fit the inside diameter of the spring 60 and extend within the spring 60. Movement of the rod 33 downward moves the head portion 33a out of engagement with the valve member 13 to allow automatic movement of the valve member 13 under control of the diaphragm 16 and spring

18 in like manner to the usual prior art thermostatic expansion valves.

The pressure within the chamber 59 is controlled by a heating element 61 which may be a resistance unit in good thermal relationship with a bulb 62. The bulb 62 is communicatively connected to the chamber 59 by a capillary tube 63 and the chamber 59, bulb 62 and tube 63 form a sealed interconnected system 63a. The system 63a may contain a quantity of temperature sensitive, volatile fluid or the system could be completely filled with a liquid having a substantial change in volume with change in temperature so that the pressure within the system 63a is hydraulic rather than the pressure of the volatilized vapor. The bulb 62 might be omitted and the tube 63 connected to any suitable source of pressure. A transformer 64 has a primary coil 65 which is connected to a source of electrical energy and a secondary coil 66. One terminal of the secondary coil 66 is directly connected by means of a lead wire 66a to one end 67 of the resistance 61 and the other terminal of the coil 66 is connected by means of a lead wire 67a to a contact 68 of a room temperature sensitive switch, generally designated 69, and which may be any suitable approved commercial thermostatic instrument which acts to open an electrical circuit upon a predetermined low temperature of the temperature sensitive blade. The switch 69 might also be a manually operated switch. The switch 69 in this instance is shown as having a bimetallic blade 70 which carries a movable contact 71 cooperable with the contact 68 for controlling an electric circuit. The contact 71 is electrically connected through the blade 70 and a lead wire 72 to the other end 73 of the resistance 61. Upon closure of the switch 69 the heater 61 acts to volatilize a portion of the liquid in the bulb 62 and to force the liquid into the chamber 59, at an increased pressure, to move the abutment member 56 downward to allow the valve member 13 to function automatically under the influence of diaphragm 16 and spring 18.

The operation of the apparatus is as follows: The inlet 2 is connected to a source of liquid refrigerant supply, the outlet 3 is connected to the inlet of a refrigerant evaporator, and the bulb 15 is attached in heat exchange relation to the evaporator outlet. When the temperature in the space cooled by the evaporator is warm, the blade 70 of the switch 69, which is positioned within the cooled space, is in closed circuit position and the heater 61 will have been energized to heat the volatile fluid within the bulb 62. The pressure within chamber 59 therefore will have increased to move the rod 33 downward to allow for movement of the valve member 13 under the influence of diaphragm 16 and spring 18 so that refrigerant is supplied to the evaporator to maintain it substantially completely flooded without "frost back" in the manner, well known to those skilled in the art, of the prior art thermostatic expansion valves. When the temperature within the cooled space decreases to a predetermined low temperature, the blade 70 will part the contacts 68, 71 to deenergize heater 61, and the bulb 62 and heater 61 will cool thereby reducing the pressure within the chamber 59. Upon a predetermined low pressure being reached within chamber 59, the spring 60 will move the thrust rod 33 upward and the head portion 33a into engagement with the valve member 13 to hold the valve member

13 against its port 10 to prevent further flow of refrigerant to the evaporator. Upon a predetermined, high temperature being reached within the cooled space, the blade 10 will close contacts 68, 71 to energize the heater 61 to raise the temperature of the bulb 62. This increase in temperature of the bulb 62 will volatilize some liquid and increase the pressure therein, which will cause some fluid to flow to, and to increase the pressure within, the chamber 59 and to move the thrust member 33 downward to remove the head portion 33^a from its engaging relation with the valve member 13 so that normal flow of refrigerant again occurs.

The apparatus is particularly adapted for use in installations known to the art as multiple installations where the separate cooled spaces are to be maintained at different temperatures, or where due to the uneven heat loads in the refrigerated spaces the amount of relative refrigeration between the spaces is not constant. In the modification shown in Fig. 3, a bleed hole 75 has been made through the member 56 so that the fluid pressure from the chamber 8 can flow into the interior of the cap member 57 and a helical coil compression spring 77 has been positioned within the chamber 59. The bulb 62 has been removed so that atmospheric pressure is maintained within chamber 59, through the open end 76 of the tube 63. With this arrangement of parts, the valve operates to limit the maximum pressure at which the valve member 13 will allow flow of fluid through the port 10. As is well known to those skilled in the art, any desired maximum operating pressure may be obtained by using the correct ratio of spring forces. In the event the desired maximum operating pressure is sub-atmospheric, the spring 77 could be dispensed with as is also well known to the prior art. When the pressure within the cap member 57 is high, the pressure will act against the annular member 55 to contract the chamber 59 and as the pressure decreases to the predetermined high or maximum operating pressure, the pressure within the chamber 59 and the force of the spring therein, if the maximum pressure is greater than atmospheric pressure, will move the member 56 downward and the portion 33^a out of engagement with the valve member 13. Other applications of the apparatus will be apparent to those skilled in the art.

It may now be seen that this invention provides a single apparatus for use in refrigerating systems by which it is possible to regulate the flow of refrigerant to, and to maintain, an evaporator substantially completely flooded with refrigerant and to also provide in the same unit a means for preventing the flow of refrigerant irrespective of the evaporator condition.

What we claim and desire to secure by Letters Patent of the United States is:

1. In a device of the character described, a first casing having a passageway therethrough with a valve port, valve means cooperable with said port to control flow of fluid through said passageway, said casing having an opening therethrough leading to said port, a second casing secured to said first casing and closing said opening, an abutment member having an aperture therethrough, a tubular member carried by said second casing and extending toward said port and through said aperture to provide a guide means for said abutment member, resilient means interposed between said abutment member and said valve means, means positioned by said tu-

5 bular member and operable to adjustably position said abutment member for adjusting the force exerted by said resilient means, a thrust member extending through and guided for reciprocal movement by said tubular member and having a portion engageable with said valve means, and power means carried by said second casing and acting to move said thrust member into engagement with and to move said valve means toward a flow restricting position.

2. In a device of the character described, a first casing having a passageway therethrough with a valve port, valve means cooperable with said port to control flow of fluid through said passageway, said casing having an opening therethrough leading to said port, a second casing secured to said first casing and closing said opening and having an abutment, an abutment member having an aperture therethrough, a tubular member carried by said second casing abutment and extending toward said port and through said aperture to provide a guide means for said abutment member, resilient means interposed between said abutment member and said valve means, means positioned by said tubular member and abutting against said second casing abutment for positioning said abutment member to adjust the force exerted by said resilient means, a thrust member extending through and guided for reciprocal movement by said tubular member and having a portion engageable with said valve means, and power means carried by said second casing and acting to move said thrust member into engagement with and to move said valve means toward a flow restricting position.

3. In a device of the character described, a first casing having a passageway therethrough with a valve port, valve means cooperable with said port to control flow of fluid through said passageway, said casing having an opening therethrough leading to said port, a second casing secured to said first casing and closing said opening, a wall in said second casing, an abutment member having an aperture therethrough and having a threaded portion, a tubular member carried by said second casing wall and extending toward said port and through said aperture to provide a guide means for said abutment member, resilient means interposed between said abutment member and said valve means, means positioned against said second casing wall and having a threaded portion cooperable with said abutment threaded portion, said positioned means being rotatable about said tubular member to adjustably position said abutment member for regulating the force exerted by said resilient means, a thrust member extending through and guided for reciprocal movement by said tubular member and having a portion engageable with said valve means, and power means carried by said second casing and acting to move said thrust member into engagement with and to move said valve means toward a flow restricting position.

4. In a device of the character described, a first casing having a passageway therethrough with a valve port, valve means cooperable with said port to control flow of fluid through said passageway, said casing having an opening therethrough leading to said port, a second casing secured to said first casing and closing said opening, a transverse wall in said second casing, an abutment member having an aperture therethrough and having a threaded portion, a tubular member carried by said transverse wall and extending toward said port and through said ap-

erture to provide a guide means for said abutment member, resilient means interposed between said abutment member and said valve means, means positioned against said transverse wall and having a threaded portion cooperable with said abutment threaded portion, said positioned means being rotatable about said tubular member as an axis to adjustably position said abutment member for regulating the force exerted by said resilient means, means for holding said abutment member against rotation by said positioning means, a thrust member extending through said tubular member and having a portion engageable with said valve means, and power means carried by said second casing and acting through said thrust member to move said valve means toward a flow restricting position.

5. In a device of the character described, a first casing having a passageway therethrough with a valve port, valve means cooperable with said port to control flow of fluid through said passageway, said casing having a chamber adjacent said port, an abutment carried by said casing within said chamber and spaced from said port, an abutment member having an aperture therethrough and having a threaded portion, a tubular member having a polygonal external periphery carried by said casing abutment and extending toward said port and through said aperture to provide a guide means for said abutment member, resilient means interposed between said abutment member and said valve means, means positioned against said casing abutment and having a threaded portion cooperable with said abutment member threaded portion, said positioned means being rotatable about said tubular member as an axis to adjustably position said abutment member for regulating the force exerted by said resilient means, said aperture having a polygonal contour cooperating with said polygonal periphery to hold said abutment member against rotation by said positioning means, a thrust member

extending through said tubular member and having a portion engageable with said valve means, and power means carried by said casing abutment on the opposite side thereof from said port and acting through said thrust member to move said valve means in one direction.

6. In a device of the character described, a first casing having a passageway therethrough with a valve port, valve means cooperable with said port to control flow of fluid through said passageway, said casing having a transverse wall spaced from said port, an inverted cup-shaped member positioned intermediate said port and said transverse wall and having an aperture through the transverse wall portion of said cup-shaped member, an outwardly extending flange on said cup-shaped member adjacent the open end thereof, a tubular member carried by said transverse wall and extending toward said port and through said aperture to provide a guide means for said cup-shaped member, a helical coil compression spring interposed between said extending flange and said valve means, a cylindrical member positioned intermediate said valve means and said transverse wall and rotatable about said tubular member and having an end wall abutting said transverse wall, said cylindrical member being externally threaded adjacent its other end, said cup-shaped member being internally threaded for threaded reception of the threads of said cylindrical member, means to rotate said cylindrical member to move said cup-shaped member to adjust the force exerted by said spring, a thrust member extending through said tubular member and having a portion engageable with said valve means, and power means carried by said second casing and acting through said thrust member to move said valve means toward a flow restricting position.
